Inventor:

Claudius Dornier.

UNITED STATES PATENT OFFICE.

CLAUDIUS DORNIER, OF FRIEDRICHSHAFEN, GERMANY.

FLYING-MACHINE STRUCTURE.

Application filed June 28, 1920. Serial No. 392,543.

To all whom it may concern:

Be it known that I, CLAUDIUS DORNIER, a citizen of the German Empire, residing at Friedrichshafen, Germany, have invented 5 certain new and useful Improvements in Flying-Machine Structures (for which I have made application in Germany, dated Sept. 10, 1916), of which the following is a specification.

10 My invention relates to flying machines and its particular object is a method of constructing and reinforcing or staying their supporting planes. In order to simplify the construction of the frame work of the flying 15 machine, as also to overcome the injurious effect exerted by the stay ropes relatively to the air resistance, there have already been constructed flying machines in the case of which all stay ropes were omitted that were 20 liable to be exposed to the head wind. The method has also been resorted to of arranging a large number of the cross-beams of 25 supporting planes after the manner of polygonal pyramids i. e. allowing their ends to meet at one point, in order to obtain a supporting deck frame of special resisting capacity. By these said means it has indeed been rendered partially possible to obtain the object desired without requiring the 30 supporting planes to be stayed or reinforced by aid of stay wires or diagonal stays or trusses.

Notwithstanding the entire absence of any outer supports for the wings is bound to 35 produce a great want of safety, so that, in the majority of cases, stays continue to be employed, even as in the past, in order to facilitate the work of fitting the parts together. However, in spite of all it has so far 40 been impossible to obtain by aid of the known methods of construction, a perfectly satisfactory way of mounting and fixing the supporting plane to the hull, and vice versa, which will readily stand subsequent static 45 tests.

The present invention aims at overcoming the aforementioned defects in that, by aid of the least possible number of cross beams and stays and by the advantageous manner 50 of connecting the same, there is obtained a simple and definite form of construction complying with full static requirements.

In the case of the flying machine according to this invention, each section of the supporting plane is provided with two cross beams having a common point of intersec-

tion. From the said point of intersection of the cross-beams, forming the frame of the supporting plane, there arises a truss which acts as an intermediate support. The two 60 additional supports are formed by the points where the two cross beams are joined to the hull of the flying machine.

In this manner, it will be observed, there will be required in the case of a monoplane 65 but one truss and two cross beams for each side. There is thus obtained, besides a simple, statically satisfactory construction (the calculation of which is particularly easy) of those members, which serve to 70 transmit the stress of the entire system, the least weight possible, and the slightest frontal resistance. But besides this, the operation of mounting and dismounting the supporting planes is very much facilitated. 75 The intersecting two cross-beams transmit, conjointly with the truss, all the forces acting on the plane section on to the hull.

In order to enable the several forces acting on the surfaces to be taken up in a satisfactory manner, ribs are joined to the cross beams. A specially favorable connection will be obtained by interposing intermediate joists, lodged at the cross beams between these latter and the said ribs. 85

The invention is applicable with like advantage to multiple-deck aeroplanes. In this case, each supporting plane section may be connected immediately with the hull by means of a rod or stay fixed at the point of 90 intersection of the two cross beams. However, the simplicity of the static structure will be maintained, and the frontal resistance still more reduced on the points of intersection of the cross beams, belonging to 95 the second and third surface sections, respectively, not being connected by means of a long stay or truss directly to the hull, but by a somewhat shorter stay or truss to the point of intersection of the first surface section. 100 On the other hand, in the case of very big spans, the upper cross beams besides being stayed or trussed up at their point of intersection (which is disposed comparatively far to the outside), may be additionally stayed, 105 and this more to the inward, by means of intermediate trusses. Besides this, it will depend upon the shape and size of the supporting planes whether the intersecting cross beams are to be extended beyond their point 110 of intersection or not. Still, it will be found expedient to extend at least one of said

cross beams beyond the point of intersection, say, about as far as the tip of the wing.

Various structures embodying the subject matter of my invention are illustrated in the accompanying drawings, forming part of this specification.

In the drawings—

Figs. 1 to 3 are front and side elevations and a plan, respectively, of a monoplane,

10 Figs. 4 to 6 corresponding views of a biplane,

Figs. 7 and 8 a front and side elevation, respectively, of one section of a large sized biplane, and

15 Fig. 9 a plan of a flying machine having strongly tapering supporting planes.

In the case of the monoplane according to Figs. 1 to 3, the frame of each section or 20 half of the supporting plane is formed by two intersecting cross beams *b* and *c* fixed to the hull. A truss *a* runs along a vertical plane, from the point of intersection *s* of the cross beams, which is disposed at the outside portion of the supporting plane section, to the hull of the flying machine.

In the case of the biplane according to Figs. 4 to 6, the upper supporting planes are trussed up in the same manner as described above relatively to the monoplane. 30 The lower, smaller planes are likewise fitted out with two intersecting cross beams *f* and *g*. The points of intersection *t* and *u*, corresponding to the cross beams *b*¹, *c*¹ and *f*, *g*, are disposed vertically below each other, each lower plane being supported relatively to the upper by a perpendicular truss or stay *e*. The cross beams *b*¹, *c*¹ of each upper supporting plane are provided with intermediate joists *h* and *i*, which serve as intermediate 40 bearings for the ribs (not shown) to which the outer skin is fixed.

In the case of the large sized flying machine illustrated by Figs. 7 and 8, the supporting planes are primarily trussed up in the same way as that described with reference to the flying machine according to Figs. 4 and 6. But, besides this, the large upper plane, the point of intersection for the cross beams of which is disposed rather far to the outside, may be further trussed up by intermediate truss members *k* and *l*, respectively, running from the center of the main truss *a*², on the one hand, to the center, and, 50 on the other, to the hull-end portion of each cross beam.

In the structure according to Fig. 9, merely the front cross beam *b*³ is extended beyond the point of intersection of the cross beams, while the rear beam *c*³ stops at said point.

In the case of all the structures herein-

before described, the main stays *a*, *a*¹, *a*² are lodged at right angles to the longitudinal axis of the flying machine, and thence run from the points of intersection of the cross beams downwards to the hull of the flying apparatus. This arrangement will be found to be the most advantageous relatively to the strains to which the structure is subjected. Notwithstanding, the arrangement may be modified, and instead of running the main stays diagonally downwards, they may be made to run diagonally upwards; further they may be disposed otherwise than at right angles to the longitudinal axis of the flying machine.

I claim:—

1. In a flying machine in combination, a supporting plane, a pair of cross beams extending from the hull substantially diagonally across said supporting plane so as to meet in one point and a stay obliquely extending between said hull and the meeting-point of said cross-beams.

2. In a flying machine in combination, a supporting plane, a pair of cross beams extending from the hull substantially diagonally across said supporting plane so as to intersect each other and a stay obliquely extending between said hull and the point of intersection of said cross beams.

3. In a multiple-deck flying machine in combination, a plurality of superposed supporting planes, a pair of cross beams extending from the hull substantially diagonally across each supporting plane so as to intersect each other, a stay obliquely extending between said hull and the point of intersection of the cross beams of the upper supporting planes, and an upright stay connecting the points of intersection of the cross beams of the superposed supporting planes.

4. In a multiple-deck flying machine in combination, a plurality of superposed supporting planes, a pair of cross beams extending from the hull substantially diagonally across each supporting plane so as to intersect each other, a stay obliquely extending between said hull and the point of intersection of the cross beams of the upper supporting planes, an upright stay connecting the points of intersection of the cross beams of the superposed supporting planes and auxiliary stays connecting the middle of said oblique stay with the bases and with points intermediate between the bases and the point of intersection, respectively, of the cross beams of the upper supporting plane.

In testimony whereof I affix my signature.

CLAUDIUS DORNIER.
